UNITED STATES PATENT OFFICE.

THOMAS E. BARNUM, OF MILWAUKEE, WISCONSIN, ASSIGNOR TO THE CUTLER-HAMMER MFG. CO., OF MILWAUKEE, WISCONSIN, A CORPORATION OF WISCONSIN.

CIRCUIT-CONTROLLER.

1,170,728.

Specification of Letters Patent.

Patented Feb. 8, 1916.

Application filed May 11, 1914. Serial No. 837,833.

To all whom it may concern:

Be it known that I, THOMAS E. BARNUM, a citizen of the United States, residing at Milwaukee, in the county of Milwaukee and State of Wisconsin, have invented new and useful Improvements in Circuit-Controllers, of which the following is a full, clear, concise, and exact description, reference being had to the accompanying drawing, forming 10 a part of this specification.

This invention relates to improvements in circuit controllers and more particularly to those of the so-called drum type. In order to disclose the nature and characteristic features of the invention, the same has been illustrated in the accompanying drawings as embodied in a controller particularly adapted for use in connection with motor operated washing machines to effect automatic reversal of the driving motor at regular intervals.

It should be understood, however, that the invention is not limited to the specific structure shown and is susceptible of advantageous use in various other relations.

In the accompanying drawings, Figure 1 shows the controller with a section of its inclosing casing broken away to disclose the control mechanism principally in elevation, 30 but partially in section. Fig. 2 is an end elevation of Fig. 1. Fig. 3 is a section on line 3—3 of Fig. 1. Fig. 4 is a section on line 4—4 of Fig. 1 and, Fig. 5 is a diagrammatic view showing one circuit arrangement for the controller.

Referring to Fig. 1, the controller includes a revoluble drum section 10 coöperating with relatively stationary contact fingers 11, 12, 13, 14 and 15 and two additional fingers 16 and 17 to engage stationary contacts 18 and 19 respectively. It is of course to be understood that the drum section may be provided with any preferred number and arrangement of contact segments; that the 45 number and arrangement of the contact fingers may be likewise varied as desired and that the additional contacts and fingers may be omitted if preferred. The drum section 10 is revoluble to coöperate with different contact fingers to vary the electrical connections of the controlled motor and the contact fingers 11 to 17 inclusive are adjustable toward and away from the drum section and contacts 18 and 19 to make and 50 break circuit. The contact fingers 11 to 17

are operable automatically under certain conditions and manually operable at will.

The foregoing and other parts of the controller are housed within a box or casing 20. The drum is fixed to a shaft 21 having 60 bearings 22 in opposite ends of the casing. The contact fingers 11 to 17 are all mounted upon a common insulating block 23 secured to and supported by two members 24 extending radially from and fixed to a shaft 25. 65 The shaft 25 is arranged in a parallel relation with the shaft 21 and is provided in opposite ends of the casing with suitable bearings 26. The supporting base for the contact fingers thus has a pivotal movement with the shaft 25 as its axis whereby it may be moved into either of the two positions illustrated in full and dotted lines, Fig. 3. In the full line position it supports the contact fingers 11 to 15 in operative relation with respect to the drum and the fingers 16 and 17 in engagement with the stationary contacts 18 and 19. Upon movement to its dotted line position it carries all of the contact fingers away from their 70 respective coöperating drum segments and stationary contacts. The angular position of the contact fingers under the former conditions is indicated by full lines and under the latter conditions by dotted lines, Fig. 3. 75 The stationary contacts 18 and 19 are both fixed to an insulating base 27 fixed to brackets 28 within the casing and to the rear of the shafts 21 and 25. Both contacts 18 and 20 19 are of similar construction and, as shown 80 in Fig. 3, the contact 19 comprises a strip extending over the drum shaft and having a downwardly projecting contact portion 19^a at its free end to be engaged by the contact 17. The insulating base 27 also 85 affords a support for suitable fuses 30 and binding posts 31 for the contact fingers. As illustrated in Fig. 3, the contact fingers may be connected to the binding posts 31 by flexible conductor 32. The drum section 90 and contact fingers, as illustrated, are of conventional types and accordingly need no detailed description.

The member 23 carrying the several contact fingers is biased to its dotted line position and is adapted to be releasably latched in its full line position. The aforesaid bias of said member is effected by a spring 33 surrounding the left-hand end of the shaft 25, Fig. 1, and having one end secured to 105 110

the casing 20 and its other end secured to one of the members 24 fixed to said shaft. A lever 34 fixed to the right hand end of the shaft 25 provides for movement of the member 23 to its full line position to set the contact fingers in operative position as aforesaid. This lever carries a pawl 35 adapted to latch with a relatively fixed pawl 36 when the support for contact fingers is moved to its full line position. Either pawl, however, may be disengaged from the other to release the lever 34 and thus permit the spring 33 to move the contact fingers outwardly. The latch 35 is normally held in effective position by a spring 37 and is adapted to be tripped by a pin 38 in the handle of the lever 33, which pin is operable at will by a push-button 39. The pawl 36, on the other hand, constitutes one arm of a bell-crank lever 40 forming the armature of an electro-magnet 41. The arrangement is such that the pawl 36 is rendered effective as a latch when the magnet 41 is energized, and, conversely, is rendered ineffective when the magnet is deenergized. Thus provision is made for release of the lever 34 at will by tripping of the pawl 35 and for automatic release of said lever by deenergization of the magnet 41. The magnet 41 is preferably of the low voltage type to automatically release the lever upon failure of voltage. The magnet 41 may, in practice, be of any preferred design and located as desired. As illustrated, the same is of the conventional form and is housed in a box 42 secured to or formed integral with the casing 20 and provided with an opening 43 through which the armature 40 projects.

The operation of the drum is effected through the following means, illustrated in Figs. 1 and 4. The shaft 21 has revolubly mounted thereon two disks 50 and 51. These disks have overlapping hub flanges 52 and are revoluble relative to one another as well as to the shaft 21. They are, however, connected to one another through a concentric coiled spring 53 disposed between them. As best illustrated in Fig. 4, one end of the spring is connected to the hub flange of the disk 51 while the other end of said spring is secured to a lug 54 provided at the outer periphery of the disk 50. The disk 50 is also provided on its periphery with two substantially diametrically disposed lugs 55 and 56 while disk 51 is provided with similar lugs 57 and 58, but disposed in an opposed relation with respect to the lugs of the disk 50. The lugs 56 and 58 are provided to receive therebetween a lug 59 carried by a radial arm 60 fixed to the shaft 21 while the lugs 55 and 57 are provided to receive therebetween a lug 61 projecting from a worm segment 62 revolubly mounted upon the shaft 21.

With the aforesaid arrangement, should

the worm segment be moved in either direction it would drive one of the disks in the same direction while the spring 53 would tend to cause the other disk to follow and through its engagement with the lug 59 rotate the shaft 21. On the other hand, the spring provides a yielding connection between the worm segment and the shaft whereby the latter may be restrained from movement while the former is operated to store up energy in said spring and this is the action provided for. It is provided for by pawls 63 and 64 pivotally supported on the walls of the casing 20 in such a relation that each may latch with the shaft lug 59 when in certain position and, also, in such a relation with respect to the worm segment as to be tripped thereby in certain positions of the latter.

The worm segment, as will hereinafter appear, is power-operated and effects the operation of the shaft in the following manner assuming the parts to be in the positions illustrated in Fig. 4. As illustrated in this figure the lug 59 is engaged and is latched by the pawl 64 and hence, if the worm segment be moved in a counter-clockwise direction it will drive in the same direction the disk 51. The disk 50, on the other hand, will be locked against movement in this direction by the lug 59 so long as said lug is latched by the pawl 64. In consequence, the spring 53 will be tensioned until the worm gear strikes and trips the latch 64. Thereupon the lug 59 and disk 50 will be freed and the energy stored in the spring 53 will drive both in a counter-clockwise direction and thereby turn the shaft 21 and drum section in the same direction. This movement will continue until the lug 59 strikes the pawl 63 and is latched thereby whereupon the parts will come to rest. Then, if the movement of the worm segment be reversed, it will drive the disk 50 in a clockwise direction to tension the spring 53 while the disk 51 is held stationary through the lug 59 and the latch 63. When, however, the worm segment strikes and trips the latch 63 the lug 59 will be freed and the energy stored in the spring 53 will be expended to drive the disk 51 and the lug 59 in a clockwise direction to reverse the rotation of the shaft and restore the drum to its former position. Thus, during operation of the worm segment the drum section of the controller remains stationary, but after a predetermined movement of the segment it is mechanically actuated with a quick action in a direction corresponding to the direction of rotation of the segment. In consequence, if the controller be designed to effect reversal of the controlled motor by reversal of its movement and said motor be used to drive the worm segment it will automatically effect its own reversal at definite intervals.

As will hereinafter appear, the controller illustrated is designed for this operation. When in one extreme position it establishes connections for forward operation of the motor and when in its other extreme position establishes reverse connections for the motor. As the drum passes from one extreme position to another, it opens the motor circuit, but only momentarily as its continued movement to circuit closing position is insured by the spring 53.

Returning to the details of construction, the worm segment is driven by a worm 65 fixed to a shaft 66 having suitable bearings 67 in opposite walls of the casing, said shaft extending at right angles to the shaft 21. Thus, if the shaft 66 be connected to the controlled motor or to the machine driven by said motor, the result will be as above described. In practice it is usually desired to use one or more resistance elements in connection with the controller and, as shown in Figs. 1 and 3, a number of resistance elements 68 are housed in the casing 20 above the controller contacts.

Referring to the circuit diagram in Fig. 5, the drum section of the controller is shown as provided with eight contact segments 70 to 77. These segments are divided into two sets, one set including the contacts 70 to 73 adapted in one extreme position of the drum to engage fingers 11 to 14, and the other set including segments 74 to 77 adapted in the other extreme position of the drum to engage fingers 12 to 15 inclusive. The two positions of the drum are indicated by dotted lines *a-a* and *b-b* and it is to be understood that the drum, when brought to rest, always assumes one of these two positions. The segments 70, 71, 74 and 75 are electrically connected and the segments 72, 73, 76 and 77 are electrically connected. The controller is shown as controlling the continuity of circuit and direction of operation of a series motor 78 having an armature A and series field winding F. The motor 78 will be assumed to effect operation of the drum in the manner above described.

As shown, the drum is in position *a* and in this position completes circuit from line L to contact 18 and finger 16 by conductor 79 through the motor field winding F and series resistance R by conductor 80 to contact finger 12 and segment 71 across to segment 70 and finger 11 by conductor 81 through the motor armature from left to right by conductor 82 to finger 13 and segment 72 across to segment 73 and finger 14 by conductor 83 to finger 17 and contact 19 to line L'. With such connections the motor will operate in a predetermined direction and operate the drum, as above described. Thereupon segments 70, 71, 72 and 73 will leave their respective contact fingers and thereby momentarily in-

terrupt the motor circuit, after which segments 74, 75, 76 and 77 will engage fingers 12, 13, 14 and 15 respectively. This recloses the motor circuit to finger 12 as already described, thence to segment 74 across to segment 75 and finger 13 by conductor 82 through the motor armature from right to left by conductor 84 to finger 15 and segment 77 thence to segment 76 and finger 14 by conductor 83 to line L', as already traced. This effects a reversal of the flow of current through the motor armature and in consequence a reversal of the direction of operation of the motor with the results already set forth. The diagram also shows the magnet winding 41 as connected from contact finger 16 by conductor 85 through said winding by conductor 86 to finger 17. Accordingly, said winding is connected across the motor circuit and is subject to deenergization upon failure of voltage. This winding, it will be remembered, must be maintained energized to effect retention of the contact fingers in operative relation with respect to the drum and to the stationary contacts 18 and 19.

The utility and advantages of the movable contact fingers will now be readily apparent. Upon failure of voltage the latching means for the fingers will be automatically tripped thereby releasing said fingers and in consequence effecting interruption of the motor from circuit. Again, manual tripping of said latching means enables the release of said fingers to interrupt the motor circuit at will. Further, it is often desirable to inch or tease the controlled motor and the contact fingers may be readily operated for this purpose through the medium of the lever 34. Still further, the contact fingers may, if desired, be arranged to leave their respective contacts simultaneously and thereby simultaneously interrupt circuit at a multiplicity of points to minimize the arcing, or, conversely, circuit interruption may be limited to certain fingers. Thus all necessity for additional contacts for manual control is eliminated.

In brief, the controller thus provided is functionally of a duplex character being susceptible of automatic operation for certain purposes and of manual operation for other purposes. On the other hand, the controller is structurally unitary in character with many apparent attending advantages.

What I claim as new and desire to secure by Letters Patent is:—

1. In a circuit controller, in combination, a plurality of relatively stationary contacts and an automatically operated contact member to coöperate therewith, said contacts being movable out of operative relation with respect to said member to break circuit in any position of the latter and having manual and automatic controlling means,

2. In a circuit controller, in combination, a plurality of stationary contacts, an automatically operated contact member to co-operate therewith, said contacts being movable out of operative relation with respect to said member to break circuit in any position of the latter, and means insuring against arrest of said automatically operated member except in a position whereby circuit may 5 be reclosed by return of said contacts to operative relation therewith.
3. In a circuit controller, the combination with a movable contact device, of relatively stationary contacts to be engaged thereby, 15 said device having automatic operating means controlled thereby and said relatively stationary contacts being movable out of operative relation with said device to interrupt the controlled circuit and thereby 20 effect arrest of said device.
4. In a circuit controller, the combination with a movable contact device, of relatively stationary contacts to be engaged thereby, said device having automatic operating means controlled thereby and said relatively stationary contacts being movable out of operative relation with said device to interrupt the controlled circuit and thereby 25 effect arrest of said device and means insuring against the arrest of said device except in a position whereby the controlled circuit may be reclosed by return of said contacts to operative relation with said device.
5. In a circuit controller, in combination, 35 a plurality of relatively stationary contacts, a movable contact device to co-operate therewith, said stationary contacts being biased to a position out of operative relation with respect to said device and means for setting 40 said contacts in operative relation with respect to said device and releasably retaining the same in the latter relation.
6. In a circuit controller, in combination, a plurality of relatively stationary contacts, 45 a movable contact device to co-operate therewith, said stationary contacts being biased to a position out of operative relation with respect to said device and means for setting said contacts in operative relation with respect to said device and releasably retaining the same in the latter relation, said means acting automatically under abnormal electrical conditions to release said contacts.
7. In a circuit controller, in combination, 55 a plurality of relatively stationary contacts, a movable contact device to co-operate therewith, said stationary contacts being biased to a position out of operative relation with respect to said device and means for setting 60 said contacts in operative relation with respect to said device and releasably retaining the same in the latter relation, said means acting automatically under abnormal electrical conditions and being operable at will to release said contacts.
8. In a circuit controller, in combination, a revoluble contact device, a plurality of relatively stationary contacts to co-operate therewith and having a common supporting member adjustable to remove said contacts from operative relation with respect to said device and automatically responsive releasing means for said supporting member also 70 operable manually.
9. In a circuit controller, in combination, 75 a revoluble contact device, a plurality of contacts to co-operate therewith, a common support for all of said contacts adjustable to move the same into and out of operative relation with respect to said device and biased to move the same out of operative relation and means for latching said support in position to retain said contacts in operative relation with said device.
10. In a circuit controller, in combination, 80 a revoluble contact device, a plurality of contacts to co-operate therewith, a common support for all of said contacts adjustable to move the same into and out of operative relation with respect to said device and biased to move the same out of operative relation and electro-magnetically controlled means for latching said support in position to retain said contacts in operative relation with 85 said device.
11. In a circuit controller, in combination, a revoluble contact device, a plurality of relatively stationary contacts to be engaged thereby, a common supporting member for 90 said contacts biased to a position to remove said contacts from operative relation with said device and electro-magnetically controlled means for latching said support in position to retain said contacts in operative relation with said device, said means being 95 operative automatically and at will to release said support.
12. In a circuit controller, in combination, a plurality of relatively stationary contacts and a movable contact device co-operating 100 therewith, said device being movable in opposite directions to either of two circuit closing positions and when at rest always occupying one of said positions, said stationary contacts being movable away from said device to interrupt circuit and being returnable to operative relation with respect to said device to re-establish circuit.
13. In a circuit controller, in combination, 105 an automatically rotated contact device and relatively stationary co-operating contacts movable into and out of operative relation therewith to make and break a controlled circuit, said device being dependent for operation upon engagement of said contacts 115 with said device but having means associated therewith to insure predetermined positioning thereof when said contacts disengage said device during rotation of the latter.
14. In a circuit controller, in combination, 120
- 125
- 130

a movable contact device and relatively stationary coöperating contacts, said device having automatic operating means to effect repetition of a predetermined cycle of operation to vary the controlled connections and said stationary contacts being movable out of and into operative relation with respect to said device to break and reëstablish the controlled circuit.

10 15. In a circuit controller, in combination, a movable contact device and relatively stationary coöperating contacts, said device having automatic operating means effecting operation thereof at definite intervals to vary the controlled connections, and said stationary contacts being movable out of and into operative relation with respect to said device to break and reëstablish the controlled circuit.

20 16. In combination, a circuit controller, including a movable contact device and a relatively stationary coöperating contact

device and a motor controlled thereby and operatively connected to said movable contact device to drive the same, said stationary 25 contact device being movable into and out of operative relation with respect to said driven contact device to stop said motor and restart the same at will.

17. In combination, a motor and a reversing controller therefor including a movable contact device operatively connected to said motor to move in opposite directions in accordance with direction of operation of said motor and stationary contacts coöperating 35 with said device and movable out of operative relation therewith to stop said motor.

In witness whereof, I have hereunto subscribed my name in the presence of two witnesses.

THOMAS E. BARNUM.
